UNIVERSAL WRAPPING MACHINE

Leroy L. Salfisberg, South Orange, N. J., assignor
to Wrap-Ade Machine Company, Inc., Newark,
N. J., a corporation of Delaware

Application March 19, 1935, Serial No. 11,756

7 Claims. (Cl. 91—14)

My invention pertains in general to packaging apparatus and specifically relates to a construction of universal wrapping machine.

One of the objects of my invention consists in providing a universal wrapping machine capable of producing conditioned sheets of packaging material for wrapping and packaging purposes.

Another object of my invention comprises providing a construction of wrapping machine for selectively utilizing different components in various relationships for providing packaging material for wrapping purposes.

A still further object resides in the provision of a wrapping machine construction having a special form of material supply means and severing means together with an optional gluing arrangement for permitting the efficient and rapid provision of sheets of packaging material, particularly coated regenerated cellulose, for wrapping operations.

These and other objects will be apparent from the following, reference being made to the accompanying drawings which form a part of this specification and in which like reference numerals designate corresponding parts throughout.

In the drawings:

Fig. 1 is a top plan view of one embodiment of the universal wrapping machine of my invention;

Fig. 2 is a longitudinal sectional view taken along the line 2—2 of Fig. 1;

Fig. 3 is a top plan view of another arrangement of the machine of my invention;

Fig. 4 is a longitudinal sectional view of the representation of Fig. 3;

Fig. 5 is a form of cutting and gluing mechanism which is employed with my invention;

Fig. 6 is a fragmentary top plan view of another form of cutting arrangement used with my invention;

Fig. 7 is a side elevation corresponding to the representation of Fig. 6;

Fig. 8 is a front elevation of a treadle-operated machine according to my invention; and

Fig. 9 is a side view of the representation of Fig. 8.

Referring to the drawings in detail and particularly to Figs. 1 and 2, there are provided a pair of side supporting elements 1 and 2 secured in separated position by transverse rod members 3, 4 and 5. The rod members 3 and 5 are provided at their opposed ends with cushioning members 6 and 7 which may be formed of rubber or other suitable material. Upon the inner sides of members 1 and 2 there are provided a plurality of mounting receptacles 10 and 11, 12 and 13, in which transverse rods 14 and 15 are removably positioned as may be seen from Fig. 1. Upon the rods 14 and 15 rolls of packaging material 17 and 18 may be mounted as desired. This material is preferably of coated transparent regenerated

cellulose. End collars 19 and 20 are slidably mounted upon the rod 14 for securing the roll of material 17 in desired rotative position. Similar end collars 21 and 22 are mounted upon the rod 15, likewise securing the roll of material 18. It will be noted that latitude of adjustment is permitted for positioning these rolls in different relationship with respect to each other. It will also be noted that the rolls may be readily removed for substitution or renewal.

The feeding ends of material from the rolls 17 and 18 are brought down respectively under transverse members 23 and 24, extending between the supporting members 1 and 2. Under member 23 the two ends 8 and 16 of the ribbon-like packaging material are superimposed and fed around transverse rods 29 and 30 and thence around rod 31 and over the cutting platen 32. (See Fig. 2.)

Referring to Fig. 1, a rod 34 is mounted above the rod 31 and may be provided, if desired, with 20 gluing units. The construction of one of these gluing units will be apparent from Figs. 1 and 2 in which it will be seen that hook members 35 and 36 depend from the rod 34 and support the glue-containing receptacle 37. Between the hook members 35 and 36 a sleeve 38 is mounted on the rod 34 and provided with a set screw 38a for positioning the gluing unit in any desired spatial relationship transversely of the machine for effecting a gluing operation on the packaging material fed around the rod 31. Internally of the glue container 37 is a wheel 40 which dips into the glue in the container 37 and applies the same in a restricted line to the material as it passes around the rod 31. The weight of the gluing unit holds the wheel 40 against the material on rod 31, and the linear movement of the material causes the rotation of the gluing wheel 40. A scraper lid 42 covers the gluing unit and is provided with a slot through which the disc 40 may rotate against the material. This lid may be adjusted back and forth to determine the amount of glue adhering to the wheel 40. This adjustment is effected by means of screw assembly 43 as shown in Fig. 2.

Another gluing unit 42a is shown mounted upon the rod 34 and is of a construction similar to the previously described gluing unit. In accordance with the construction of my invention, these gluing units may be inserted or removed at will and especially positioned for any particular form of gluing operation, as desired.

Above the platen 32 a pair of transverse guide rods 45 and 46 are mounted between the upright members 1 and 2. Mounted for movement on these guide rods there is provided a cutting unit which, in accordance with the present invention, may be of different forms. In the first form of this cutting unit, there is provided a mounting member 47 which includes a bearing sliding upon

the guide rod 45. This mounting member 47 also includes a housing supporting a rotatably mounted cutting wheel 48. The bearing portion of mounting member 47 has a free rotative movement upon the guide rod 45 to bring the cutting wheel 48 into cutting relationship with the platen 32 under pressure. The wheel 48 has a cutting edge as will be apparent from an inspection of Fig. 2. A handle member 49 is connected by a pressure spring 50 with the mounting member 47, and is carried by the yoke 47a mounted as a swivel on rod 45.

A ball-bearing unit 51 is rotatably mounted in the handle structure as shown and is provided with a concave periphery which engages the guide rod 46. In effecting a cutting operation, the operator grasps the upper portion of the handle structure 49 and exerts a downward pressure through spring 50 to cause the cutting wheel 48 to sever the packaging material on the platen 32 while imparting a transverse sweep to the cutting unit as a whole to traverse the material. A transverse material positioning member 39 is constructed in a mechanically complementary fashion with respect to a recess provided longitudinally along the platen 32. This member 39 is mounted in slots at either end of the platen for permitting a slight vertical movement whereby the weight of the member normally depresses the packaging material within the recess of the platen 32. Before a cutting operation is consummated, the weight of this element causes the extending portion of the ribbon-like packaging material to assume an upright position extending away from the platen 32 so that the operator can grasp this portion of the material and pull it out to a desired length. Thus the operator may use one hand for feeding the material and the other hand for effecting the cutting operation as desired. In connection with the cutting operation, a board 55 is hingedly secured to the rod 3 as shown and may be provided with cutting indicia or a scale for effecting the cutting of proper lengths of the packaging material.

45 The cutting unit used in the invention is provided with gluing units as may be seen in Fig. 5. These gluing units consist of funnel-shaped glue containers 57a and 57b, having feeding pipes 58a and 58b extending down adjacent the cutting wheel 48 proximate to the material to be cut. A wire 59 extends into the opening of the pipes 58a and 58b and is connected, in each instance with pivoted elements 61a and 61b controlled in their movement by the manual pressure on the handle member 49 whereby the flow of glue to the packaging material is accordingly adjusted. As further shown in Fig. 1, the pair of glue units 57a and 57b are provided with their flow pipes 58a and 58b extending upon opposite sides of the cutting wheel 60 48 for applying a thin strip of glue to the packaging material upon both sides of the severing line. Although certain specific forms of gluing arrangements have been shown it is recognized that various modifications and changes can be 65 made to accommodate and meet the requirements of various conditions. For example, the apparatus of my invention may, when desired, dispense with the gluing arrangements associated with the handle 49, as shown in the representations of Figs. 70 3 and 4.

A further use and arrangement of the foregoing apparatus may be observed in Figs. 3 and 4 in which the roll of material 17 has been removed and in place thereof a moisture-applying roller 75 65 has been provided. A moistening pan 66 is

removably mounted beneath the roller 65 upon positioning pin 67 and may be provided with water or other fluid for moistening the periphery of roller 65. In this arrangement the ribbon feeder extending from the roll of material 18 is brought up from rod 24 around the roller 20 and under the rod 23 and thence around the other rods 29, 30 and 31 to the platen 32. Under such conditions, the cellulose packaging material is moistened as the material is fed to the platen 32. The spacing between rods 23 and 31 permits partial drying of the material before reaching the platen 32 so as to have a desired moisture treatment. Such an arrangement is particularly advantageous when it is desired to apply cellulose material to packages by the shrinkage process such as in the wrapping of bottles and the like.

Another form of the cutting unit can be seen in Figs. 6 and 7. Referring to these figures, a unitary mounting structure 70 is provided and includes a yoke having legs 71 and 72 provided with sliding bearings mounted on the guide rod 45. The upright portion of the mounting structure 70 terminates in a handle portion 75. Extending through this upright portion of the structure 70, and above the yoke members 71 and 72, there is threaded a stud 76 having a slotted end accessible for adjustment from the front of the machine. The other end of the stud is provided with a concave bearing member 77 which may be 30 composed of fiber or other suitable material. The member 77 engages the rod 46 under adjustment of the stud 76. A lock nut 78 is provided for securing the stud 76 in an adjusted position. In this arrangement, a cutting strip 80 is removably mounted upon the upper surface of the platen 32 and is secured thereto by screws 81. The strip 80 is of rectilinear construction and is preferably composed of hardened steel or a similar material. A cutting wheel 82 is rotatably mounted upon a 40 spindle 83 extending from the front of the mounting structure 70 as shown in Fig. 7. The cutting wheel 82 is of somewhat different construction than the previously described cutting wheel 48, inasmuch as the cutting wheel 82 has a flat periphery engaging with platen 32 and a side, at right angles to the periphery, engaging the strip 80. A spindle 83 is provided with a screw head 84 for permitting removal or adjustment with respect to the structure 70. A spring 85 is mounted 45 upon the spindle 83 between the head 84 and a hub of the wheel 82 for exerting pressure toward the structure 70. As will be seen in Fig. 7, the material is normally held, by weight of the member 39, in a distended position, as represented by 50 the dotted line, for enabling the operator to easily grasp the same and pull out the proper length. When the proper length has been pulled out, the handle 75 may be grasped and a transverse sweep 55 imparted to the cutting unit whereby the cooperation of cutting wheel 82 and strip 80 produces a shearing effect which severs the material. An especial advantage of such a shearing operation is that the cutting elements employed are given to long life and at the same time offer no sharp 60 edge which might be dangerous to unskilled operators. It will be noted that in both cutting operations hereinbefore described, a cutting operation can be effected in both directions across 65 the machine. Either one of the arrangements 70 of cutting unit described and depicted may be employed as desired in the various embodiments of my invention.

Figs. 8 and 9 represent a treadle-operated form 75 of the invention. In this arrangement, the cut-

ting machine is mounted upon a structure having upright leg members 90. In this instance either form of the cutting unit may be used for treadle operation, thereby enabling the operator to have 5 both hands free for wrapping and other manipulations of the packaging material aside from cutting. The cutting unit is provided with a flexible cable 92 which extends through holes in the upright members 1 and 2 to pulley units 93 and 94 10 rotatably mounted upon opposite sides of the machine as shown in Fig. 8. After passing over these pulley units the cable 92 then extends around pulley units 95 and 96. In the lower part of the structure and between a pair of the 15 legs 90, two treadles 97 and 98 are mounted for independent foot operation. The treadle 97 is connected by a coupling unit 99 with the cable 92 at a point between the pulley units 93 and 95, while treadle 98 is mechanically connected by 20 coupling unit 100 to the cable 92 at a point between the pulley units 94 and 96. Thus the operator, positioned in front of the machine, can utilize his feet to independently impart a transverse cutting motion to the cutting unit respectively 25 in opposite directions while having his hands available for other purposes in connection with the packaging operation.

The wrapping machine of my invention is universal in its aspects and has various uses which, 30 from the foregoing description and disclosure, will be apparent to those skilled in the art. Various combinations and arrangements for wrapping articles can be effected. For example, plural sheets of cellulose material of the same or different characteristics can be superimposed in varying spatial relationships for wrapping articles or forming packages. In another aspect of the 35 same machine, moistened material can be utilized for packaging by the shrinkage process. These and other uses of the invention may suggest modifications to those skilled in the art but which will not depart from the intended scope 40 of my invention. I do not therefore desire to limit myself to the foregoing except as may be 45 pointed out in the appended claims.

What I claim as new and desire to secure by Letters Patent of the United States is:

1. A wrapping machine comprising, packaging material supply and feeding means for longitudinally feeding a strip of packaging material, and severing means for detaching desired lengths of said material, said severing means including a reciprocatively mounted guide member, a cutting roller pivotally secured thereto, a plate over 55 which said material may pass and with which said roller cooperates to produce a severing action on the material, and a plurality of packaging material roll supporting means longitudinally adjustable with respect to each other for 60 positioning the respective material fed therefrom to lie in selected superimposed transverse relationship.

2. A wrapping machine comprising, packaging material supply and feeding means for longitudinally feeding a strip of packaging material, and severing means for detaching desired lengths of said material, said severing means including a reciprocatively mounted guide member, a cutting roller pivotally secured thereto, a plate over 65 which said material may pass and with which said roller cooperates to produce a severing action on the material, said feeding means

comprising a plurality of packaging material roll supporting means and including a selectively insertable moistening means operative in the place of one of said roll supporting means.

3. A universal wrapping machine comprising, 5 means for rotatably supporting roll packaging material in ribbon form, a plate over which said material is fed said plate having a shearing element, means cooperating with said plate to normally hold a section of material passing over said 10 plate in a distended position away from the plate to permit an operator to easily grasp the same to pull out a desired length of said material from the machine, and severing means actuatable transversely of said material across said plate for 15 severing said material, said severing means including a rotatable device engageable with a surface of said shearing element to produce a shearing action.

4. A machine in accordance with claim 3 in 20 which said severing means includes a reciprocative member, and a handle therefor, said roller being operable in either transverse direction for severing said material.

5. A wrapping machine comprising, means for 25 rotatably supporting a roll of packaging material of strip-like form, platen means over which said material is fed, a severing strip removably mounted on said platen, a severing structure reciprocatively mounted above said platen and carrying a roller having a flat periphery engaging with the surface of said platen to press and hold the material against the platen means and having a flat side thereof engaging with an edge surface of said cutting strip perpendicular to 30 said platen surface to produce a severing action in cooperation therewith, and means for normally holding said material in an extended position away from the surface of said platen means to permit an operator to grasp the same to pull 40 out a desired length to be severed by said severing means.

6. A wrapping machine comprising, packaging material supply and feeding means for longitudinally feeding a strip of packaging material, 45 and severing means for detaching desired lengths of said material, said severing means including a reciprocatively mounted guide member, a cutting roller pivotally secured thereto, a plate over 50 which said material may pass and with which said roller cooperates to produce a severing action on the material, said movable severing means being provided with gluing means mounted thereon for applying transverse glue areas to 55 said material.

7. A wrapping machine comprising, packaging material supply and feeding means for longitudinally feeding a strip of packaging material, and severing means for detaching desired lengths of said material, said severing means including 60 a reciprocatively mounted guide member, a cutting roller pivotally secured thereto, a plate over which said material may pass and with which said roller cooperates to produce a severing action on the material, said severing means being 65 provided with gluing means for applying a plurality of strips of glue to said material, one strip being on the severed section of the material and the other strip being on the supply portion of 70 the material.
